PAPER HANDLING MECHANISM FOR ACCOUNTING MACHINES

Walter A. Anderson, Bridgeport, Conn., assignor to Underwood Elliott Fisher Company, New York, N. Y., a corporation of Delaware

Application December 30, 1938, Serial No. 248,430

1 Claim. (Cl. 197—127)

This invention relates to paper carriages for accounting machines, and more particularly to means for guiding and holding cards and the like that are adapted to be printed on such machines.

Many users of modern accounting machines require that the carriages thereon be equipped with mechanism for accommodating and holding a plurality of short forms such as, for example, employees' earning record cards and pay envelopes. These forms are arranged to be jointly inserted in the carriage at separate points and held in position for successive printing operations. Since these forms are relatively short in length in comparison to the usual length of forms, and since in many instances there is only a single line posting to be printed thereon, it is desirable that they be fed from in front of the platen to facilitate their rapid insertion and removal. Most front feed type carriages have transversely extending rods which make it inconvenient for the operator to insert short forms to a sufficient depth with respect to the printing line of the platen. Such carriages as have been equipped with mechanism to provide for this problem have sacrificed, more or less, the lateral adjustability of the guiding and holding means. Furthermore, the provision of two or more finger openings in the transversely extending rods, to facilitate insertion of the forms, tends to weaken the assembly and to impair the efficient operation of the front feed structure generally.

It is an object of this invention, therefore, to provide a front feed guiding and holding mechanism for short forms that permits ready insertion and removal of a plurality of such forms to the correct depth in accordance with the printing requirements, and in such manner that lateral adjustability of the guides to accommodate cards of varying widths is not sacrificed and the rigidity of the general front feed structure remains unimpaired.

With this and incidental objects in view, the invention consists in certain novel features of construction and combinations of parts, the essential elements of which are set forth in the appended claim, and a preferred embodiment of which is hereinafter described with reference to the drawing which accompanies and forms part of this specification.

In the drawing:

Figure 1 is a perspective view of a carriage embodying the invention,

Figure 2 is a detail sectional view showing the

means employed for mounting finger openings on the front feed bail rods, and

Figure 3 is a detail sectional view taken on the line 3—3 of Figure 2.

The invention is illustrated in connection with the type of carriage used on the machine disclosed in the application of Oscar J. Sundstrand, Serial No. 581,800, filed December 18, 1931. It is adapted to be used on the type of carriage disclosed in U. S. Patent No. 2,060,954, issued to Oscar J. Sundstrand on November 17, 1936, or on that disclosed in the U. S. applications of Walter A. Anderson, Serial Nos. 92,164 and 192,675, filed July 23, 1936, and February 26, 1938, respectively.

Carriage in general

Referring to Figure 1, the carriage is mounted for movement along a track 1. As the carriage moves from right to left, it is stopped in various columnar positions so that type bars 2 on the accounting machine may print on the work forms fed around the platen 3. The mechanism for tabulating the carriage from column to column and for returning it to its initial position is disclosed in application Serial No. 581,800. The carriage is adapted to accommodate rear fed paper such as a journal sheet 4, and front fed paper including short forms such as an employee's record card 5 and a pay envelope 6. The platen may be rotated manually by knobs 7 secured to each end of the platen shaft 8, and may be rotated automatically during operations of the machine by a feed pawl 9 cooperating with teeth on a ratchet wheel 10 secured to shaft 8. The mechanism for operating pawl 9 is disclosed in Patent No. 2,060,954.

Mechanism for guiding and holding front fed paper

For introducing front fed sheets, a plurality of guide chutes 11, 12 and 13 are provided. These chutes are formed with sides 14 which act as edge guides, and are secured on separate brackets 15 mounted for sliding movement along rods 16. The outer ends of the two outside rods 16 are secured by screws, such as 17, to upstanding arms 18 mounted for pivotal movement on the carriage side walls. Arms 18 correspond to end pieces 35 in Patent No. 2,060,954 and are mounted for pivotal movement on carriage side walls 50 in the same manner as disclosed in this patent. The opposite ends of the outside rods 16 are secured by screws, such as 19, to sides 20 of finger pieces 21; the opposite ends of the middle rod 16 are connected by screws, such as 22, to the 55

opposite sides 23 of finger pieces 21. A series of square rods 24 are similarly connected between arms 18 and sides 20 and between sides 23 of the finger pieces by screws, such as 25, as shown.

5 Pressure rolls 26 journaled in brackets 27, which are slidably mounted on rods 24, serve to hold forms 5 and 6 in feeding contact with the platen. Screws 28 provided in brackets 27 are arranged to bear against rods 24, and thereby hold pressure rolls 26 in adjusted position laterally therealong. Likewise, suitable frictional means is provided on brackets 15 to hold chutes 11, 12 and 13 in their laterally adjusted positions.

10 Finger pieces 21 are so formed as to permit the operator to insert short forms around the platen 3 to a point where the line on which it is desired to have the printing appear on such forms is in line with the printing line of the platen, these 15 finger pieces allowing room for the operator's fingers during such insertion. Referring to the afore-mentioned patents, it will be observed that the rods shown there which correspond to the rods 16 and 24 are of one continuous piece, and, 20 therefore, present an obstruction to the insertion of short forms into the desired printing alignment with the platen. The interposition of finger pieces 21 as above described, overcomes this 25 obstruction and permits the rapid removal and insertion of front fed short forms into correct 30 printing alignment. It has been found, however, that such interposing of the finger pieces, and especially where there must be a plurality of them, as illustrated in the present disclosure, 35 generally tends to weaken the front feed assembly and thereby impairs its smooth and easy operation. To overcome this, there is provided a 40 series of brace rods 29 arranged to be connected between arms 18 and sides 20 of finger pieces 21 and also between sides 23 of the finger pieces in the following manner.

45 The opposite ends of the square shafts 24 are turned "round" adjacent their ends, as shown in Figure 2. A pair of clamp members 30 and 31 are arranged to embrace rods 16 and 24 and are clamped firmly thereon by means of a screw 32 passing through said members and threaded in a rearwardly extending arm 33, the forward end of which fits flush against the surface of member

51 Arms 33 are apertured to receive the opposite ends of brace rods 29; and screws, such as 35, threaded in the ends of these rods provide a secure connection between side walls 20 and 23 of finger pieces 21, and arms 18. These clamping 5 units, shown in detail in Figures 2 and 3, are indicated generally at 36 in Figure 1, and one is provided adjacent each arm 18 and adjacent sides 20 and 23 of each finger piece 21.

10 In operation, the front feed bail mechanism 10 is swung forwardly from the position shown in Figure 1, known as the closed position, to open position. This removes rolls 26 from contact with platen 3, and brings chutes 11, 12 and 13 into substantially vertical position ready for insertion of the forms. The forms are inserted 15 downwardly into the chutes to correct printing alignment, and the front feed bail is then swung back to the closed position as shown. It has been found in practice, that by using the novel arrangement of the clamp members with the brace rods 29, when finger openings are provided, that opening and closing of the bail mechanism may be accomplished as smoothly and easily as heretofore, notwithstanding the inclusion of such finger 20 openings, the entire structure retaining its former rigidity the same as though rods 16 and 24 extended unbroken across the entire carriage. 25

30 While the form of mechanism herein shown and described is admirably adapted to fulfill the objects primarily stated, it is to be understood that it is not intended to confine the invention to the one form of embodiment herein disclosed, for it is susceptible of embodiment in various 35 forms, all coming within the scope of the claim 35 which follows.

What is claimed is:

36 In a paper carriage having a roller platen, a movable front feed bail mechanism including sets of three spaced parallel rods extending transversely of said platen, underslung bridges mounted in spaced relation between said sets of rods and connected to the rods at the ends thereof, to facilitate introduction of short forms around said platen, and clamping means extending 40 between the ends of the rods in each set to give rigidity to the mechanism. 45

WALTER A. ANDERSON.
